SEWING MACHINE ATTACHMENT

Davis Marinsky and Louis H. Morin, Bronx, N. Y.

Application May 25, 1938, Serial No. 209,889

4 Claims. (Cl. 112—2)

This invention relates to sewing machines and particularly to what might be termed attachments to machines of this type to convert a standard machine into a stitching machine designed to perform certain specific functions, such for example as attaching one or more cords or strands to an elongated tape, for example, the stringer tape of a separable fastener, and also in laying another strand on the tape or cord and arranged longitudinally thereof in the stitching operation, and in retaining the last mentioned strand in position by the stitches employed in securing the cord or cords to the tape. More particularly, the attachment comprises means for positively and adjustably controlling the feed of the workpiece through the machine as well as means for guiding the lay of the strand on the workpiece or the cord attached thereto, as well as in the provision of a series of switches cooperating with the various strands and the workpiece fed into the machine to automatically stop the machine upon the consumption thereof or in the event of breakage occurring therein. The novel features of the invention will be best understood from the following description and annexed drawings in which one embodiment of the invention is disclosed, and in which the separate parts of the machine are designated by suitable reference characters in each of the views, and in which:

Fig. 1 is a front view of a machine made according to our invention with parts of the construction broken away and in section.

Fig. 1A is a sectional detail view showing part of the gearing employed in the attachment.

Fig. 2 is a plan and sectional view showing the various attachments as applied to the table of the machine and omitting the frame of the sewing machine proper.

Fig. 3 is a sectional view substantially on the line 3—3 of Fig. 2 on an enlarged scale.

Fig. 4 is a view similar to Fig. 3 showing certain parts on an enlarged scale.

Fig. 5 is a partial section on the line 5—5 of Fig. 4.

Fig. 6 is a partial section on the line 6—6 of Fig. 3.

Fig. 7 is an enlarged detail view of a part of the construction shown in Fig. 2 with parts of the construction broken away.

Fig. 8 is a sectional detail view showing the automatic catch for the control treadle of the machine.

Fig. 9 is a detail view of a part of the con-

struction shown in Fig. 1 as viewed from one side of the machine.

Fig. 10 is a sectional detail view of a clutch drive.

Fig. 11 is a partial section on the line 11—11 of Fig. 10.

Fig. 12 is a perspective view diagrammatically illustrating the method of stitching two cords to a tape and in laying a strand in zigzag fashion upon one of the cords and interlocked with the stitchings.

Fig. 13 is a diagrammatic view illustrating the electric circuit controlling the various switches and mechanisms of the machine; and,

Fig. 14 is a detail view of a part of a tape made according to the invention, indicating the contour thereof.

For the purpose of illustrating one method of carrying the invention into effect, we have shown in the accompanying drawings certain attachments applied to one type and kind of sewing machine of standard construction, commonly referred to as a "Singer High Speed Sewing Machine" such as used in various factories and shops. In this connection, it will be understood that the fundamental and basic principles of the attachment herein illustrated, aside from the specific structure of certain parts, is applicable to other makes of machines of this type. In the same manner, while the present attachment is specifically designed for the performance of certain operations upon a predetermined workpiece which is illustrated in the accompanying drawings as a matter of example, it will also be apparent in this connection that the basic principles of the various attachments are applicable for the performance of similar functions upon different kinds and classes of workpieces wherein the principles of operation herein shown and described are applicable. It will thus be apparent that the drawings and following description are illustrative of one method of carrying our invention into effect.

In the drawings, 15 represents the table or work bench of a factory machine and is usually composed of wood. This work bench or table is simply re-cut to adapt the various attachments thereto substantially in accordance with the structure later described. At 16 in Fig. 1 of the drawings, is diagrammatically illustrated the frame of the sewing machine proper, the arm of the frame being indicated at 17, and the vertical head at the free end of the arm at 18. At 19 is shown a base plate of the frame which is arranged in and supported in connection with the

table 15 in the usual manner. At 20 is shown an electric drive motor hung beneath the table 15 and coupled with the drive shaft 21 of the machine through a belt 22 operating in connection with a pulley 23 on the motor shaft and a pulley 24 on the drive shaft. Arranged beneath the base plate 19 is the usual driven shaft 25, commonly termed the hook shaft, geared to the shaft 21 through the vertical shaft 26 and the inter-engaging bevelled gears on the respective shafts as seen at 27 and 28 in Fig. 1 of the drawings. At 29 and 30 are the guide rollers over which the needle thread 31 passes prior to passing through the usual guides on the head 18 and then being threaded through the needle 32 of the machine, note Fig. 4. At 33 is shown the rocker shaft arranged and supported upon the under surface of the base plate 19; and at 34 is shown the usual presser foot operating rod supported in the head 18. At 35 is shown diagrammatically the bobbin case of the machine.

All of the above described mechanisms, which represent the main parts of the machine in connection with which our attachment operates, are old and well known in the art; and are simply diagrammatically illustrated in order to understand the association of the various attachments with such parts in order that the operation of the attachment will be clearly understood. At this time, it is also well to mention that the usual workpiece feed mechanism is removed as well as the usual presser foot. Substituted for the presser foot is a workpiece guide 36 which is supported in connection with the rod 34 and serves to guide the tape 37 in its movement beneath the needle 32 of the machine, as well as to guide the top and bottom cords or strands 38 and 39 to dispose the same above and below the tape 37 at one edge portion of the tape. At this time it will be well to note that one of the strands will be twisted in one direction, for example to the right, and the other strand will be twisted to the left in order to maintain a balance as between said cords and the tape to avoid undesirable distortions, but, however, not to interfere with a desired curve formed in the tape as a whole by virtue of the stitching operation; the curvature of the resulting stitched product being indicated in Fig. 14 of the drawings.

In addition to the particular stitching operation which is to be performed to attach the cords or strands 38 and 39 to the tape 37 as diagrammatically illustrated in Fig. 12 of the drawings by the needle thread 31, it is also desirable to employ as the bobbin thread 40, a special form of strand. This may be what we commonly term a tinsel; that is to say, a fine wire spirally wound upon a fine cotton or other strand. On the other hand, this bobbin thread 40 may be in the form of a rayon or similar thread, depending entirely upon the type of links or scoops which are to be attached to the stringer tape in forming a separable fastener; that is to say, the tinsel is used when metal links are applied to the fastener, and the rayon thread when cellulose acetate or similar links are employed.

In the stitching operation we also prefer to lay in zigzag fashion another strand 41 upon the upper cord 38. This strand will correspond to the companion strand 40; that is to say, when tinsel is employed at 40, a tinsel will be employed at 41; and when 40 is a rayon thread or strand, 41 will be a corresponding thread. The thread or strand 41 will be guided over the work-piece in the manner later described in forming

the laterally offset or zigzag appearance as at 41a in Fig. 12 of the drawings.

The workpiece guide 36, see Fig. 4, consists of a wide plate having a fixed guide block 36a at one side thereof which guides the edge of the tape 37 to which the cords are attached and also guides the position of the upper cord 38; whereas the other edge of the tape 37 is guided by an adjustable block 36b which will compensate for strips of different widths, the plate 36 having an elongated aperture 36c to provide for this adjustment. The forward end of the guide plate 36 extends upwardly as seen in Fig. 4; and a transverse strip 36d is arranged to support the tape 37 in raised position just forwardly of the needle so as to provide a free passage of the tape as well as the top and bottom cords 38 and 39 into position beneath the needle; the cord 39 being guided into position beneath the plate through the eye or other guide 42. The plate 36 has a large aperture 36e in the upper surface thereof through which the needle 32 passes as well as the strand 41.

Supported upon the rod 34 is an oscillating lever 43 having a forked end 43a and a hook end 43b, the latter having a recess as seen at 43c to receive the strand 41 to lay the same in the zigzag fashion diagrammatically illustrated in Fig. 12 of the drawings by moving the strand intermittently across the path of the needle after each stitching operation of the needle so that the strand 41 will be held in position in the zigzag lay by the stitches 31a; that is to say, after one downward movement of the needle, the strand 41 for example, will be moved to the left, viewing the machine from the front side thereof, and then after the next stitching operation, the strand 41 will be moved to the right, and this operation continues throughout the entire length of the stitching operation. It will, of course, be apparent that the machine may be so timed as to perform alternate transverse movements of the strand every other stitch, but the structure as described is preferred in order to securely arrange the strand 41 upon the cord 38. It will be understood that the strand 41 passes through the recess 43c downwardly through the aperture 36e in the plate 36, as will appear in Fig. 4 of the drawings.

At this time it is desirable to call attention to the fact that one of the features of the invention resides in the provision of a machine which may be termed automatic in operation; that is to say, after the machine has been put into operation it will continue to operate without the care and guidance of an operator, the machine being automatically stopped when the end of any particular thread, strand, or workpiece is reached, or upon the breakage of the various elements. To carry this automatic operation into effect, we have provided means for controlling the feed of the workpiece through the machine and particularly in providing an intermittent feed so that a constant and even arrangement of stitching will be formed in the resulting finished product; the length of the stitches being governed by suitable tension devices.

We provide a bracket attachment 44 which is secured to the table of the machine and preferably arranged adjacent and in back of the head 18. The rear end portion of the bracket extends downwardly in the opening 15a formed in the table 15, note Fig. 3. This end portion of the bracket has a transverse pivot rod 45 in connection with which a swinging arm 46 is mounted,

the arm being yoke-shaped in form as seen in Fig. 2 of the drawings, and supporting a long bearing 46a at its free end in which is supported a shaft 47 having outwardly of one end thereof a feed roller 48, having an integral gear 49 at one side thereof. The arm 46 has centrally thereof a rearward extension 46b, see Fig. 2, upon which is pivotally supported a control lever 50 which normally supports the roller 48 in the position shown in Fig. 3. However, by swinging the lever 50 upwardly, the cam surface 50a thereof may be brought into engagement with the projection 44a on the bracket 44 so as to cause the roller 48 to be swung upwardly to disengage it from its companion roller against the action of an adjustable spring 51 arranged upon a rod 52 pivotally supported in connection with the bracket 44 as seen at 53.

The bracket 44 also supports a shaft 54 which projects at one side of the bracket, and arranged on the extended end is a companion feed roller 48a having an integral gear 49a, the latter being adapted to mesh with the gear 49 of the roller 48. The outer end of the shaft 54 is also preferably provided with an additional support 55 in the form of a ball clutch, note Figs. 10 and 11; and this clutch is supported in connection with the bracket as seen at 55a. A yoke-shaped lever 56 is arranged upon the shaft 55 and also has a ball clutch engagement with the roller 48a as indicated at 57. The clutch construction is such as to provide intermittent rotation of the rollers 48, 48a in the oscillatory movement imparted to the lever 56 by a link 58 coupling the forked end of the lever 56 with a lever 33a secured to the usual oscillating shaft 33, see Fig. 3, so that in the oscillatory movement imparted to the shaft 33 as in a conventional machine, this motion is transmitted to and utilized for the intermittent feed of the feed rollers through the ball clutch structure employed in connection with the roller 48a. It will be understood that the rollers are rotated to feed the tape away from the needle, as will be apparent; and the clutch as at 57 will engage the roller in the feed thereof; whereas the clutch 55 will engage the roller to hold it against rotation in the oscillatory movement of the lever 56 as will be apparent.

The shaft 54 extends through the opposite end of the bracket 44 and has thereon a worm 54a which engages a worm gear 59 on a vertically arranged crank shaft 60 supported in the bracket 44, note Fig. 2. Coupled eccentrically with the crank shaft 60 is one end of a connecting rod 61, the other end 61a of which is adjustably supported in an oscillatory arm 62 or in an elongated slot 62a in said arm. The adjustment here provided is to control and regulate the operation of a switch tripping disc 63 which is adjustably supported on another vertical shaft 63b, supported in the bracket 44, and which is intermittently actuated through the arm 62 by a ball clutch construction as indicated at 65, see Fig. 7, similar to the ball clutches 55, 57, to provide the constant feed of the trip disc 63 in one direction so that the trip 63a of the disc will actuate a control switch 64 at the completion of each cycle of revolution of the disc 63 to automatically stop the machine, it being understood that the disc 63 is set in the starting position indicated in Fig. 2 of the drawings by manually rotating the same. This switch is employed to stop the machine just prior to the consumption of the bobbin thread, or in other words, the tinsel and rayon thread 46, so that at this time the operator may replace

5 a new bobbin; the adjustment of the rod or link 61 being provided to compensate for various lengths of the bobbin thread as will be apparent. While these bobbins will require replacement from time to time in the automatic operation of the machine, one operator may nevertheless care for numerous machines by reason of the time factor required in the consumption of the bobbin thread.

10 Arranged on the bracket 44 is a gear housing 66 in which is supported a vertical shaft 67, the lower end of which extends through the plate 19 and has a bevelled gear 68 meshing with a bevelled gear 69 secured to the shaft 25. On the shaft 67 is a pinion 70 meshing with a large gear 71 arranged on a shaft 72, see Figs. 1A and 6; the gear 71 meshing with another gear 73 on a crank shaft 74 carrying an eccentric, swiveled and grooved block 75 in connection with which the forked end 43a of the lever 43 operates to impart the reciprocating motion to the tinsel or rayon guide hook 43b controlling the lay of the strand 41. While the gearing employed is such as to provide the lay of the strand 41 as illustrated diagrammatically in Fig. 12 of the drawings, it may be modified to suit other forms of construction, the only essential feature being that the strand 41 be arranged out of the path of the needle in the stitching operation of said needle. It will also appear from a consideration of Fig. 2 of the drawings that the housing 66 forms a support for the switch 64. It will thus be seen that the entire feed mechanism becomes a part of the bracket structure and may be readily attached and detached from the machine by simply making the necessary connections with the various operating and supporting links or shafts. This materially simplifies the installation of the attachment insofar as this operating mechanism is concerned. While parts of the mechanisms are arranged in housings, it will be understood that substantially the entire attachment may be arranged in a housing or hood to conceal and protect the same; sufficient openings being provided to adjust the various parts and assemble the workpieces as will be apparent.

30 Supported beneath the table 15 of the machine on the upright sides 15b thereof are rods 76, 76a, 50 for detachably supporting spools 77, 77a upon which are arranged the cords 38 and 39, respectively. These cords extend upwardly through eyelets or apertures 78, 78a, formed in the table, note Fig. 1; and then pass through switch devices 55 79, 79a, for automatically stopping the machine when the ends of the cords 38, 39 are reached or in the event of a breakage in the cords. The switch devices 79, 79a have switch arms 80, 80a which are supported in open circuit position by the passage of the cords 38, 39, therebeneath.

60 Another switch device 81 is supported in open circuit position by the thread 31, see Fig. 1; the switch 81 being in the form of a pivoted lever supported in open position by a wire link 82 having an eye at its free end through which the thread 31 passes. The other end of the lever has a light spring 83 engaging the same so that after the thread 31 is consumed at a point between the rollers 29 and 30, the link 82 is released and the spring 83 will move the switch 81 into closed circuit position. Another switch 84 is provided to control the tinsel, rayon or other strand 41, which comes from a spool 41a supported above the head 18 of the machine. After passing through an adjustable tension device 85, the

thread passes under an end 84a of a freely pivoted switch lever 84, see Fig. 9, the thread passing over two guides 86, at opposite sides of the end 84 so that the thread 41 is consumed or breaks between the guides 86, the lever 84 will drop by gravity to complete the circuit which will stop the machine.

The cords 38 and 39 also pass through adjustable tension devices 87, 87a, note Fig. 2, which are similar to the conventional thread tension devices commonly employed in sewing machines and similar to the devices 85. As these devices are well known, no specific description thereof is deemed necessary. The switch mechanism 84, tension device 85 and the roller 41a, are all supported in a bracket 88 attached to the head 18, as noted in Figs. 1 and 9 of the drawings. Another bracket or plate 89 is secured to the table 15 forwardly and in direct alinement with the needle of the machine. In this bracket is a fixed tape guide 90 and an adjustable tape guide 91, note Fig. 2, to aid in guiding the tape into and through the machine, and especially into the plate 36. Adjacent the guides 90, 91, is an adjustable tension plate 92, the tension of which is controlled by a spring 93 arranged on an upwardly extending pin 94 with an adjustable milled nut 95 on the pin to regulate the tension of the spring 93. By increasing and decreasing the frictional engagement of the tension plate 92 with the tape 37 the tension on the tape will be controlled and thus a constant length of the stitches 31a may be maintained. The stitch length is regulated through the usual means of a sewing machine, which controls the oscillation of the shaft 33. This means is not shown as it forms no part of the invention.

Also arranged upon the bracket or plate 89, see Figs. 2 and 3, is a gravity operating switch arm 96 disposed between two raised tape supporting surfaces 97 so that when the end of the tape is reached, the circuit through the switch 96 will be closed and the machine automatically stopped. This switch is arranged sufficiently in advance of the needle to cause the machine to stop before the end of the tape has been reached. On the bracket 89 is a tape guide pin 98 around which the tape passes when disposed in a vertical position and the tape being twisted upon entering the guides 90, 91, and in passing beneath the switch 96. The supply of tape comes from a spool or reel 99 supported on the top of the table 15 at the left of the machine.

On each of the pins 76, 76a, supporting the spools 77, 77a, are detachable plugs 100, 100a, by means of which the spools 77, 77a, may be quickly attached and detached in renewing the supply of cord in the use of the machine. At 101 is shown a main switch which controls the supply of electric energy to the motor 20 from a source of supply as diagrammatically illustrated in Fig. 13. It is also preferred that a transformer 102 be employed in the circuit to the various switch devices in order to cut down the voltage of such devices as will be apparent. In Fig. 8 of the drawings, we have diagrammatically illustrated the foot treadle 103 of the machine which is pivoted as at 104 and attached to the treadle is a rearwardly projecting catch rod or finger 105 adapted to engage a spring 106 to hold the treadle 103 in a depressed or operating position to provide the continuous automatic operation of the machine without the care or attention of the operator.

Coupled with the dog 106 is the core 107 of a solenoid 108 which is in circuit with all of the switch devices 64, 79, 79a, 81, 84, 96, so that upon the completion of the circuit through any of such switch devices, the core 107 will be drawn inwardly and the dog 106 released to permit automatic movement of the treadle to the stop position in which operation the rod 109 coupled with the treadle or the extension 105 actuates the usual combination clutch and brake mechanism of the motor 20, commonly employed in machines of the type under consideration, which mechanism is diagrammatically illustrated at 110 in Fig. 13 of the drawings to declutch the motor from the drive of the machine and to quickly brake and retard the machine operation. Also included in the circuit to the solenoid 108 is an electric bulb 111 which is arranged in a suitable support 112 upon the top of the table so that a signal will be given to the operator carrying for a number of the machines in question. The particular type of signal used may be varied to suit different uses of the machine and an audible signal may be employed as will be apparent.

In the use of the machine as herein illustrated, it will be understood that the workpiece 37, the strands 38 and 39, and the threads 31 and 40, as well as the strand 41, are threaded through the machine in the manner illustrated, and the parts 31, 38 and 39 brought into position beneath the plate 36. If desired, the initial operations of the machine in beginning the stitching of the cords 38 and 39 to the edge of the tape may be started by hand until such time that the tape protrudes sufficiently to be passed between the feed rollers 48, 48a. The roller 48 will be raised by actuating the lever 50 to permit the placement of the tape between said rollers. Both of these rollers are grooved as indicated at 48b, note Figs. 2 and 11, to receive the corded edges of the tape, and when in proper position the lever 50 is returned to provide tensional engagement of the roller 48 with the workstrip or tape 37 after which the treadle 103 may be depressed and set into its locked position as indicated in Fig. 8 and the machine will continue to operate automatically.

In the above operation, the disc 63 is set in the position shown in Fig. 2 of the drawings. Upon completing one revolution of the disc 63, which of course rotates very slowly due to the particular type of intermittent feed provided, the amount of thread 40 from the bobbin will have been consumed or substantially consumed and the machine will then be automatically stopped by the tripping of the switch 64. The above operation will be repeated several times during the consumption of a full length of the workpiece or tape 37. When the latter has been consumed, the actuation of the switch 96 will automatically stop the machine and a new supply of the tape will be inserted in the machine. If desired, the end of one tape may be attached to the end of the other tape to form continuous tape lengths. A thin gummed tape may be used for this purpose. The same applies to the renewal of the cords or strands 38 and 39, the machine being automatically stopped on the consumption of either or both of these strands through the operation of the switches 79, 79a, or the switch elements 80, 80a, thereof.

In the event of the consumption of the thread 31 or breakage in this thread, the switch 81

will be automatically operated to stop the machine for the renewal thereof; see Fig. 1 and the same also applies to the strand 41, which is controlled through the switch 84.

From the foregoing it will be apparent that the machine is entirely automatic; thus materially economizing on the cost of producing stringer tapes of the character under consideration especially from the standpoint that a single attendant can care for the necessary renewals required in a large series of machines. Of course, the skill of an operator insofar as performing the stitching operations are concerned and in the handling of the several work-pieces is dispensed with. In this way a very even and regular form of stitching is provided. It will also be apparent that the curvature in the resulting workpiece, illustrated in part at 31a in Fig. 14 of the drawings, may be regulated by increasing or decreasing the length of the stitch through the adjustable means hereinbefore referred to.

It will of course be apparent that by changing the structure of the plate 36 and the rollers 48, 48a, the machine may be adapted to work-pieces of various kinds and classes especially in the production of workpieces of great length where automatic machine operation of this type and kind is desirable.

The intermittent feed of the tape operates in synchronism with the needle operation in order to maintain the proper pull on the tape with respect to the stitching operation. It will be apparent that the tension on the cords, also contributes to some degree in controlling the curvature of the resulting tape.

Having fully described our invention what we claim as new and desire to secure by Letters Patent, is:

1. A stitching machine for producing a beaded edge tape for separable fastener stringers wherein in the tape is curved throughout the length thereof, said machine having means for forming a stitching, means for guiding a tape through the stitching means, means for guiding two cords twisted in opposite directions through the stitching means with one cord disposed above and the other cord below the tape and with both cords at one edge portion thereof whereby both cords will be stitched to the tape in one line of stitching, and separate adjustable tension devices engaging the tape and each of said cords to control the degree of curvature of the resulting stringer tape and the line of stitching employed in securing the parts together. 55

2. A stitching machine for producing a beaded edge tape for separable fastener stringers wherein in the tape is curved throughout the length thereof, said machine having means for forming a stitching, means for guiding a tape through the stitching means, means for guiding two cords twisted in opposite directions through the stitching means with one cord disposed above and the other cord below the tape and with both cords at one edge portion thereof whereby both cords will be stitched to the tape in one line of stitching, separate adjustable tension devices engaging the tape and each of said cords to control the degree of curvature of the resulting stringer tape and the line of stitching employed in securing the parts together, and means for laying a metallic strand in zigzag fashion upon one of said cords and retained thereon by said line of stitching.

3. In a sewing machine for producing a beaded edge tape, means for forming a stitching, means for guiding a tape through the stitching means, means for guiding two cords through the stitching means with one cord disposed above and the other below the tape and with both cords at one edge portion of the tape whereby both cords will be stitched to the tape in one line of stitching, feed rollers arranged in spaced relation to the stitching means, and forming the sole means of feeding the tape and cords through the machine, and separate adjustable tension devices engaging the tape and each of said cords fed through said stitching means by said rollers.

4. In a sewing machine for producing a beaded edge tape, means for forming a stitching, means for guiding a tape through the stitching means, means for guiding two cords through the stitching means with one cord disposed above and the other below the tape and with both cords at one edge portion of the tape whereby both cords will be stitched to the tape in one line of stitching, feed rollers arranged in spaced relation to the stitching means, and forming the sole means of feeding the tape and cords through the machine, separate adjustable tension devices engaging the tape and each of said cords fed through said stitching means by said rollers, and means in operative engagement with the machine and adjacent said stitching means for moving a strand intermittently across the line of stitching in zig-zag manner upon one of the cords stitched to said tape.

DAVIS MARINSKY.
LOUIS H. MORIN.
